FURRING POST

Filed Aug. 26, 1927

George F. Voight.
By Atty. S. D. Enforth, Jr., Clinton Miller.

UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

FURRING POST.

Application filed August 26, 1927. Serial No. 215,588.

My invention relates to improvements in furring posts particularly adapted for attaching stucco wire in spaced order to the wall sheathing of stucco structures, although 5 also useful for other purposes; and one of the objects of the present invention is the provision of a spacing element normally frictionally fixedly locked on the forward end of a nail or driven element, but movable 10 relatively thereon when said driven element is operatively projected in the wall sheathing for attaching the stucco wire thereto preparatory to the application of the stucco composition thereagainst.

With the foregoing and other objects and purposes in view which will appear as the description proceeds, my invention resides in the combination and arrangement of parts and in the details of construction hereinafter 20 described and claimed, it being understood that changes in the precise embodiment of the invention herein disclosed can be made within the scope of what is claimed without departing from the spirit of the invention.

In the accompanying drawings—

Figure 1 is a side elevation of one of the present furring posts supporting a strand of stucco wire, seated against a fragmental portion of wall sheathing, preparatory to 30 operatively projecting the driven element thereinto for securing the stucco wire thereto;

Figure 2 is a face view of the device after the driven element has been projected in the 35 wall sheathing, showing the head of the driven element in engagement with the stucco wire for binding it on the spacing element and for holding the latter seated against the wall sheathing;

Figure 3 is a sectional elevation of the spacing element, wall sheathing, stucco wire and stucco composition;

Figure 4 is a view in elevation of the spacing element removed from the driven 45 element;

Figure 5 is a median vertical sectional view of the spacing element and elevations of portions of the driven element;

Figure 6 is a view on line 6'-6' of Fig. 1; 50 Figure 7 is a view on line 7'-7' of Fig. 5; and

Figures 8 and 9 are views on lines 8'-8' and 9'-9' respectively, of Fig. 4.

Referring to the drawings in detail, throughout which like numerals designate 55 like parts:

The numerals 1, 2 and 3, designate the wall sheathing, stucco wire and my improved furring post, respectively.

The wall sheathing 1 comprises preferably, boards secured in closely jointed order across the face of the studding and like frame timbers of the structure, and may, if desired, be provided with an exterior surface covering of building paper 60 4 to prevent any moisture that may penetrate the stucco composition from penetrating to the woodwork of the structure. The application of the building paper 4 is however optional, and the stucco wire 2 may, if 65 preferred, be secured, by means of the present furring posts 3, directly to the wall sheathing, and the designations "sheathing" and "wall sheathing", when hereinafter used, shall include any paper or like covering or surfacing that may be applied to the wall sheathing prior to the application of the stucco wire thereagainst.

The stucco wire 2 may comprise any wire 70 mesh or netting found suitable as a foundation and reinforcement for the stucco composition. The wire netting commonly known as "poultry wire" has been found to be entirely suitable for this purpose.

The furring posts 3, which form the 75 present invention and which are adapted for securing the stucco wire 2 in spaced relation to the wall sheathing 1, embody, each, a driven element comprising a headed nail 5 having its lower end preferably pointed, 80 and a spacing element formed of an oblong strip of sheet metal having a portion intermediate its ends folded double and comprising a base plate 6 disposed substantially at right angles with the nail 5, the axis of 85 which it crosses, a sub-plate 7, which seats against the upper side of said base plate, and an upright member 8 having intermediate portions struck flat-wise in opposite directions to form nail engaging bands or 90 loops 9, 10, and 11, between a division of which the nail projects and against the inner walls of which it bears sufficiently to become normally frictionally held against 95 accidental movement relatively thereto, but longitudinally slid able therebetween when 100 105

said nail is forcibly projected a proper distance in the wall sheathing against which the spacing element is seated.

The arrangement of the bands 9, 10 and 5 11, are intended to be such relative to the upright member 8, that the nail 5 when disposed between said bands, will lie substantially in the plane of said member (see Fig. 1).

10 The intermediate portion of the upper edge of the upright member 8 is cut away to form, on opposite sides of the nail 5, wire seats 12 for supporting the stucco wire 2, and wire retaining projections 13 for limiting lateral movement of said wire on said seats.

The base plate 6 is provided with an opening 14 to permit the passage therethrough of the nail 5 as it is driven into the wall 20 sheathing, and to facilitate the free movement of the nail through said plate and opening, the latter may be formed considerably larger than the diameter of the body of the nail (see last five figures of the 25 drawings).

The spacing element is preferably assembled on the driven element at the factory and is normally frictionally held on the forward end thereof (see Fig. 1) to resist accidental removal therefrom; and to apply the device for securing the stucco wire to the wall sheathing, it is simply necessary to project the forward end of the device including the spacing element, through one of 30 the interstices or meshes of the wire with the nail disposed along one side of one of the strands of said wire, and then drive the nail into the wall sheathing until the head of the nail engages and binds the strand on 35 one of the wire seats 12, and binds the spacing element against the wall sheathing.

The furring posts may be disposed along the sheathing at such intervals as may be found best suited for the work to be performed. I have found that spacing them 45 about 8 inches apart provides ample fastening and spacing for the stucco wire at present in general use for reinforcing stucco material.

50 After securing the stucco wire to the wall sheathing, the stucco composition 15 is preferably applied by spreading it on the sheathing and on and around the stucco wire and furring posts until a stucco coating of suitable thickness is obtained.

I claim:

1. In means of the character described, a strip of flat metal having a spacing portion with its lower end bent substantially at right angles to form a wall engaging portion, the spacing portion having bands struck flat-

wise in opposite directions to form nail holding means, the wall engaging portion being provided with an aperture to receive a nail held by the nail holding means.

2. In means of the character described, a strip of flat metal having a spacing portion with its lower end bent substantially at right angles to form a wall engaging portion, the spacing portion having bands struck flat- 70 wise in opposite directions to form nail holding means to hold a nail substantially in the plane of the spacing portion, the wall engaging portion being provided with an aperture to receive a nail held by the nail holding 75 means.

3. In means of the character described, a strip of flat metal having a spacing portion with its lower end bent substantially at right angles to form a wall engaging portion, the spacing portion having a band struck flat- 80 wise out of the plane thereof to form nail holding means, the wall engaging portion being provided with an aperture to receive a nail held by the nail holding means.

4. In means of the character described, a strip of flat metal having a spacing portion with a lath seat at its upper end and its entire lower end bent substantially at right angles to form a wall-engaging portion, the spacing portion having a loop struck therefrom to form nail-holding means, the wall-engaging portion being provided with an aperture to receive a nail held by the nail-holding 90 means.

5. In means of the character described, a strip of flat metal having a spacing portion with a lath seat at its upper end and its entire lower end uniformly bent substantially at right angles to form a wall-engaging portion, the spacing portion having a loop struck therefrom to form nail-holding 100 means.

6. In means of the character described, a strip of flat metal having a spacing portion with its entire lower end uniformly bent substantially at right angles to form a wall-engaging portion, the spacing portion having bands struck flat-wise in opposite directions to form nail-holding means.

7. In means of the character described, a strip of flat metal having a spacing portion with its entire lower end uniformly bent substantially at right angles to form a wall-engaging portion, the spacing portion having bands struck flat-wise in opposite directions to form nail-holding means to hold a nail substantially in the plane of the spacing portion.

In witness whereof, I have hereunto set 120 my hand this 15th day of August, 1927.

GEORGE F. VOIGHT.
